EDGE TRIM GAUGE

Mark R. Manning, Toledo, Ohio

Application January 6, 1939, Serial No. 249,547

1 Claim. (Cl. 33—76)

This invention relates to setting straight edges for marking and cutting.

This invention has utility when incorporated in locating for marking or trimming the edges of sheet stock, as wall board or wall paper, more especially as to removing the selvage and wall paper strips which have been pasted and folded to have the paste inside.

Referring to the drawing:

10 Fig. 1 is a plan view of an embodiment of the invention in connection with a straight edge and trimmer for wall paper selvage;

Fig. 2 is a section on the line II—II, Fig. 1, showing the device with parts broken away;

15 Fig. 3 is a section on the line III—III, Fig. 2, showing the device in mounted position at the track;

Fig. 4 is a view of the device from the left of Fig. 2; and

20 Fig. 5 is a view of the trimmer having the device in conjunction therewith.

Paper as in strips may be coated with paste or adhesive on the back side or upper surface as the paper is placed with the decorated surface or face down on table 1. As so pasted, the paper 2 is folded on itself inwardly from its overall length to have its ends 3 abut and thus expose the printed or decorated surfaces throughout and have the paste-carrying surface concealed.

25 30 In such folding with the pasted portion on itself to leave the printed side exposed, decoration 4 may come to margin 5 in determining selvage distance at one side and a different margin 6 for determining selvage on the opposite side. In

35 35 the set-up hereunder, marker plate or strip 7 is shown as having effective straight edge 8 and adjacent thereto countersink 9 with overhang 10 forming a track. In this track as a guide may run trimmer 11 having track coating means 12 and cutter disk 13 directed by the track coating means 12 to have this cutting disk 13 travel at the straight edge 8 in trimming the paper 2.

Facility in carrying out this operation is effected hereunder by accessory block 14, shown as 40 having transversely thereof pair of parallel guide ways or parts 15, in each of which is rod 16 or 17 as a gauge finger having offset terminus 18. These rods may be relatively short for taking care of a set of operations which may run from 45 50 $\frac{3}{8}$ inch for trimming off the narrower side and up to $1\frac{1}{4}$ inch for trimming off the wider side of the paper or strip. While for greater clearance, say up to 7 inches or more, longer rod may be used. In either instance the rod 16, 17, is 55 readily slidable in the guide-way 15 transversely

of the direction of the block 14 as resting on the plate 7.

At the adjusted position away from the block 14 for the terminal finger 18, such may be locked by a set screw 19. In this locking, the terminal 5 finger 18 may be at the edge of the paper 2. Such location may thus determine a line of travel for the cutter 13 at the clearance from the edge of the paper as directed by the straight edge 8, the position of the straight edge having been 10 determined by the location of the pointer 14. The straight edge is thus placed to direct the operation of the cutter for removal of a strip at the edge of the wall paper, which wall paper has been folded to have its pasted side inside and the 15 printed side exposed. This position may be adopted for wider gauge as placed by the rod 16, for locating the trimmer line of cut to be taken off a strip of stock. For the narrower or other selvage edge of said stock, the rod 17 may be positioned and held so adjusted by the set screw 19. Notwithstanding there has been located two 20 positions for the offsets or fingers, it is in order to use one of these accessories at the paper edge for one of the cuts. For such use, the trimmer 25 11 may travel freely along and even thrust or push the guide finger to be clear of interference of the trimmer operation. This is effected without disturbing the line of set for said finger in its 30 clearance as to the straight edge, and is accordingly for the full dimension or range for the paper to be cut. Similar handling may be had in replacing the straight edge in operation according to the other gauge. It is to be noted that in this disclosure there is available at all times 35 full freedom for trimmer travel as to the straight edge 8 of the plate 7.

In practice, it may be desirable to supplement the accessory by installing or adapting a pair thereof to the track.

40 This block 14 is shown having depending portion 20 as a cooperating part, opposed to which is a plate 21 at the opposite side of the block 14. The plate 21 has flange 22 riding on the under side of the track 10. This holds the block 14 45 down and the plate 21 as opposed to the plate 20 allows for this sliding freely along the track of the plate 7 at the straight edge 8 with the gauge fingers positioned to be adjusted transversely of the extent of this track. The plate 50 21 may be adjusted for nicety of undergripping due to slot 23 and clamping nut 24 as to bolt 25, also mounting plate 20 if separate.

In the set-up hereunder, it is thus seen that the plate 7 may be placed on the folded pasted 55

paper 2 with an accessory block 14 adjacent each end of the paper. As so positioned and with the trimmer therebetween, such trimmer 11 may be operated along the track for the full length of 5 the paper independently of any special handling of either gauge device or locator as such may be shoved clear of the paper as the trimmer strikes such. This progressing of the accessory by the trimmer can serve to progress the offset 18 as 10 an indicator from the initially set position to be noted by the operator of the trimmer as to whether such is maintaining the desired relationship for the clearance along the paper.

These locators or gauge means may be shoved 15 clear of the plate 7 as to its track by the trimmer or slid clear thereof, say for other use of the plate. However, when it is only desired to shift the plate from the table say to hang or be suspended, the locators may be left in position with 20 or without the trimmer at the track. The plate is free as normally for locating the straight edge and the plural fingers mean that there may be one adjustment for one side of the paper strip and a different adjustment for the opposite side 25 as determined say for a batch of paper or of room lengths for cutting. With this assembly for the pair of fingers in each block, there is available to the worker a speed of operation in the trimming with accuracy in determining paper edges for butt or wire edge or other type of 30 finishing as may be in order.

The block 14 with its pair of guides and limiting of such to complementary track coacting 35 means renders this device progressively coactive in practice. Instead of an individual accessory to such purpose there may be at a side of the cutter clear of the trimming wheel an extension 26 from the body of the cutter 11, whereby the cutter coaction with the track serves as the directing means for this gauge. Under such cir- 40

cumstances, the cutter 11 (Fig. 5) is herein shown with the extension block 26 serving as the block 14, wherein the set screws 19 adjust the respective rods 16, 17, for such to locate their offset termini 18 differently as to the opposite 5 edges of the paper. Thus the location at one end for the paper strip and progressing of the cutter therealong at the adjusted position may leave the observer free to check the offsets 18 as 10 to their proper clearance position travel line as the cutter is operated or with the cutter idle in the trimmer 11.

Herein the block is a unit of small dimension, readily placed in the operator's kit or pocket, and available for accurate dimension use in the 15 wide range in practice. Accuracy and speed in adjustment may be effected, whether the set screws be set by hand or screw driver. The general feature is that the block is of coacting features for definitely locating with the track for 20 free travel therealong.

What is claimed and it is desired to secure by United States Letters Patent is:

A marker plate having a straight edge and a countersunk guide forming an overhanging track 25 parallel to said straight edge, a runner embodying a block spanning between the edge and guide, there being complementary way means fixed with the block directing the block for freely traveling as directed by the guide and coacting with the 30 straight edge against otherwise shifting as to the guide, there being port means through the block clear of the plate, pointer means in and protruding from the port means to overhang in spaced 35 relation from the straight edge, and set screw means in the block transversely of the port means for anchoring the pointer means in adjusted position as to the block.
